UNITED STATES PATENT OFFICE

169,137

SHAPED TEXTILE FABRIC

Harry M. Goldman, New Rochelle, N. Y.

Application May 24, 1952, Serial No. 19,878

Term of patent 3½ years

(Cl. D92—1)

To all whom it may concern:

Be it known that I, Harry M. Goldman, a citizen of the United States of America, residing in New Rochelle, county of Westchester, and State of New York, have invented a new, original, and ornamental Design for a Shaped Textile Fabric, of which the following is a specification, reference being had to the accompanying drawing, forming part thereof, wherein the figure on the drawing is a plan view of a piece of shaped textile fabric showing my new design.

I claim:

The ornamental design for a shaped textile fabric, substantially as shown.

HARRY M. GOLDMAN.
